ELECTRICAL VIBRATOR UNIT

Emile C. Guedon, Audubon, N. J., Alexander D. Burt, Narberth, Pa., and Frederic Shoup, Oaklyn, N. J., assignors to Radio Corporation of America, a corporation of Delaware

Application February 28, 1934, Serial No. 713,324

26 Claims. (Cl. 171—97)

The present invention relates to radio power supply systems, and more particularly to vibratory-contact, circuit-controlling means for use in connection with a direct-current transformer or inverter system for supplying anode and other operating potentials to radio apparatus. Preferably such a system may be of the type disclosed in a co-pending application of Frederic Shoup and Alexander D. Burt, Serial No. 689,720, filed September 16, 1933, and assigned to the same assignee as this application.

As shown in the application above referred to, a circuit controlling device of the vibratory contact type, in connection with a suitable transformer, may be utilized instead of batteries for the supply of operating potentials to automobile radio receiving apparatus and the like, whereby all the power for such apparatus may be obtained from the single low voltage source provided by the automobile storage battery.

A form of vibrator device of the character under consideration, for use in connection with a transformer, may include a pair of primary contacts, a pair of secondary contacts, and an electric vibrator as motor means for alternately connecting said contacts for each winding with the respective input and output circuits of the system. Additional operating contacts for the vibrator motor means may also be provided.

Vibratory contact circuit-controlling devices of the type above described may be constructed within relatively small dimensions advantageously for use in portable and automotive radio apparatus and the like. However, the vibratory contact or armature elements thereof may be subjected to various degrees of vibration as well as other adverse conditions of operation incidental to automotive and portable use.

Interference with the normal smooth vibratory action of the armature or moving element may ordinarily affect the amplitude and continuity of the voltage output from a power supply system involving a vibratory contact circuit controlling device sufficiently to interfere with the quiet operation of the radio apparatus associated therewith. Furthermore, mechanical noise of operation and electrical disturbances inherently characteristic of vibratory electrical contact apparatus may be radiated from the device and therefore may interfere with the quiet operation of the radio apparatus.

It is, therefore, an object of the invention to provide an improved vibrator device of the character described, wherein the above limitations are

overcome while retaining desirable features of compactness and simplicity in construction.

It is a still further object of the present invention to provide an improved and simplified vibrator or vibratory-contact circuit controlling device which is not appreciably subject to the foregoing disadvantages and which is of rugged, compact construction particularly adapted for use in power supply apparatus in vehicles without being adversely affected by vibration, and acceleration or deceleration of the vehicle.

It is another object of the invention to provide an improved vibrator-motor-actuated switching mechanism for alternately establishing and breaking a plurality of circuits in a direct current transforming system.

Another object of the invention is to provide, in a system of the above character, including a transformer having a divided winding, an improved means for establishing a circuit alternately through one part and then through a remaining part of the winding.

Another object of the invention is to provide an improved electro-magnetically actuated device for alternately making and breaking a circuit, said device including an armature arranged for movement within the field of an electro-magnet, between or along, but out of contact with the poles of said electro-magnet.

A further object of the invention is to provide an improved circuit making and breaking device in a radio power supply system which embodies vibratory circuit making and breaking means, including a swinging armature or reed, arranged for movement along, but never in contact with, an active pole face of an actuating electro-magnet, and an energizing winding for the electro-magnet which includes a shunt circuit closed to decrease the energization of said electro-magnet below an effective point when the circuit is closed.

A further object of the present invention is to provide a vibratory contact or inverter device which, while being completely electrically and mechanically shielded, to prevent sound and electrical radiation, may readily and quickly be opened for inspection and adjustment.

It is a still further object of the present invention to provide an improved circuit controlling means of the vibratory contact type for power supply for radio apparatus and the like, which is adapted to be mounted in and form part of said apparatus, and which is electrically and mechanically shielded therein as a unit.

In a present preferred embodiment of the invention, a vibratory circuit controlling device is

provided with a flexibly mounted vibrator unit on a relatively heavy base. The base forms part of a sound and electrical shielding container for the vibrator unit and associated electrical circuit elements. The armature element of the vibrator unit is arranged to stand vertically and to lie in a plane transverse of the base and common to the direction of travel and major movement of a vehicle, whereby motion of the armature is at a right angle to said plane, and the operation of the armature is thereby substantially unaffected by the spring action and the acceleration or deceleration of the vehicle.

To complete the sound and electrical shielding, the heavy base is arranged to receive a plurality of nested or concentric, spaced shield cans on screw threaded shoulders which serve simultaneously as mounting and spacing means therefor. This construction provides a dead air space between the shield cans for sound insulation and provides effective electrical shielding for the apparatus contained therein.

The device is adapted to be mounted in an opening in the shielding of a receiver or other apparatus and to be connected with a transformer element, hereinafter referred to, within the apparatus shielding. The vibrator unit includes contact and motor means arranged for smooth operation and easy adjustment with a maximum degree of compactness.

Further, in accordance with the invention, the unit itself, the armature and certain of the contact elements of the vibrator motor means are arranged to have predetermined periods of vibration. The armature is also arranged to move between the poles of an actuating electro-magnet close to, but out of contact with, the adjacent faces of said poles, whereby the armature is prevented from striking the poles, thereby obtaining smoother and quieter operation.

The invention will, however, be better understood from the following description when considered in connection with the accompanying drawings, and its scope will be pointed out in the appended claims.

In the drawings, Fig. 1 is a view in perspective and substantially full size, of a vibrator-rectifier device embodying the invention, and with shield covers removed for inspection;

Fig. 2 is a cross-sectional view of the same, on the same scale and with shield covers in place;

Fig. 3 is a sectional view, and on the same scale, of a portion of the apparatus shown in Figs. 1 and 2, taken on the line 3—3 of Fig. 2;

Fig. 4 is a further sectional view, and on the same scale, of the portion of the apparatus shown in Fig. 3, taken on the line 4—4;

Fig. 5 is a circuit diagram of the apparatus of Fig. 1 to 4 inclusive, in connection with a power supply circuit and transformer therefor;

Figs. 6, 7, and 8 are front, side and top views respectively, and substantially full size, of a vibrator device embodying a modification of the invention, Fig. 8 being partly in section taken on the line 8—8 of Fig. 7;

Fig. 9 is a front view partly in section, of a further modification similar to the device shown in Figs. 6, 7, and 8, but on a reduced scale, and in connection with a schematic diagram of a power supply circuit including a transformer with which it operates; and

Fig. 10 is a side view, partly in section, of a detail modification of a portion of the device of Figs. 1, 2, 3 and 4.

Referring to Figs. 1 to 4, inclusive, 10 is a

relatively heavy metallic base member, preferably cylindrical in form, and provided with shoulders or stepped concentric threaded portions 11 and 12 on which are mounted correspondingly threaded concentric nested metallic shield cans 13 and 14 to form, with the base member, an electrically shielded and substantially sound-proof container. Any suitable number of spaced shield cans may be mounted by providing a suitable number of stepped threaded portions on the base, as indicated. In the present example, two such nested, spaced cans are shown.

The shield cans are entirely supported and spaced by connection with the base member 10, and are so arranged that a relatively wide air space 15 is provided between them in which may be placed sound absorbing lining material such as felt, as indicated at 16. The interior of the innermost shield can may also be lined with a similar material, as indicated at 17, thereby improving the sound absorbing qualities of the inner walls of the container.

The shield cans are preferably formed of thin sheet metal, in one piece, with threaded open ends as shown, and the base member is preferably a relatively heavy die-casting, relatively thick in cross section, as indicated more clearly in Fig. 2, to aid in preventing the transmission of sound vibrations from the interior of the container.

In the present example, the base member is formed with a hollow interior and the bottom is arranged to depend from the main body of the base member, as indicated at 18, to provide a cup or interior central well in which may be located electrical circuit elements, such as a pair of circuit controlling condensers 19—19.

Electrical leads indicated at 20, for the interior electrical apparatus are arranged to pass through the well and out from the base at the bottom to provide shielded electrical connections with external electrical apparatus hereinafter described.

To this end, the base is adapted to be mounted on and form part of the shielding of an electrical apparatus, and in the present example, is arranged to extend through an opening 21 in the apparatus shielding indicated at 22, and to be mounted on said shielding through the medium of suitably spaced ears 23, as shown in Figs. 1 and 2. The base member serves to close the opening 21 by extending through it to the interior thereof, and to complete the shielding, while at the same time it is easily removable therefrom.

The leads, electrical condensers, or other devices within the base are secured in place by filling the well with insulating compound indicated at 24. It will also be seen that the compound serves to seal the lead openings against sound leakage. Suitable electrical connections with the apparatus or circuit elements in the base are made before pouring the compound, and it will be seen that the base, apparatus, and leads may be built as one unit in the course of manufacture, the connection leads extending above and below the base, as shown more clearly in Fig. 2.

The container provides an electrically shielded and sound-proof housing for the vibrator unit 25, per se, which is flexibly mounted therein in spaced relation to the base member, as shown more fully in Fig. 2. The vibrator unit is also preferably slightly spaced from the walls of the container so that it may move independently of

and relative to the base member on a flexible mounting and spacing means.

The flexible mounting and spacing means for the vibrator unit is provided preferably by an annular flexible or resilient connecting member, or mounting sleeve 26, located between the base 27 of the unit and the shield base at 10, and engaging at its opposite ends an annular groove 28 in the unit base and a similar groove 29 in the shield base. The walls of the sleeve are thickened to provide annular inner flanges or beads 30 to fill the grooves and to provide a secure connection therewith as shown more clearly in Fig. 2.

The walls of the sleeve 26 are of sufficient thickness and stiffness to hold the vibrator unit base normally parallel with and raised above the shield base. The sleeve is of such length that the vibrator unit base is sufficiently spaced from the shield base to provide a flexible connection with the base and a length of connecting leads sufficient to provide flexibility without imparting stiffness to or breakage of the leads.

It will be noted that the walls of the tubular sleeve are tapered so that the walls lie at an angle to the vertical whereby vertical forces of vibration incidental to the operation of the device are absorbed or prevented from reaching the base by the walls of the sleeve in bending rather than by being compressed. The mounting sleeve is preferably of flexible rubber for this purpose, of sufficient stiffness, normally to support the vibrator unit without being deformed.

The vibrator unit further comprises an armature body or mass 31 movable on a pair of spaced supporting springs or reeds 32 between the spaced pole pieces 33 of an electro-magnet provided by a magnet winding 35 on a core 36 to which the pole pieces are secured.

The pole pieces 33 are flat rectangular plates arranged in parallel relation to each other on opposite ends of the core and winding to provide spaced substantially parallel pole faces 37 in opposing relation to each other.

The armature is supported for movement between or along, but out of contact with, the pole pieces of the electro-magnet on the free ends of the flexible mounting springs or reeds 32. The opposite ends of the springs 32 are secured to a mounting pedestal or central post 38 integral with the base 27. The mounting pedestal or post is also provided, at the top, with a bracket 39 on which the electro-magnet is mounted by means of suitable threaded studs 40 passing therethrough from the pole pieces.

The base 27, the pedestal 38, and the bracket 39 are preferably of insulating material, whereby the various pieces of apparatus attached thereto and spaced, may be operated at differing electrical potentials. To protect the bracket 39 from breakage when the pole pieces are clamped down too tightly, a separator plate, preferably of brass, is inserted between the pole pieces and the bracket as indicated at 41.

The armature mounting springs straddle the pedestal 38 on opposite sides and are secured to the pedestal and base on suitable side lugs 42 by means of clamping screws 43. The springs are provided with electrical terminal lugs 44 to which electrical connection is made with the leads 20 as indicated.

It will be noted that the mounting springs 32 are flat adjacent to the fixed ends and that they are provided with curled or flanged edges 32a more adjacent to the armature whereby the re-

gion of bending of the springs is confined to the fixed ends of the springs and at a distance from the armature mass. This permits the armature to operate more uniformly about substantially a fixed pivot on a relatively long radius arm. 5

The mounting springs are given an initial set or bend, adjacent to the fixed ends to place them under tension, thereby to apply a biasing force to the armature in a direction away from the pole pieces. When the armature is in its normally retracted position away from the pole pieces, as shown in Figs. 1, 3 and 4, it engages the free end of a short spring contact member 45 which is clamped or secured at the opposite end to the mounting pedestal 38, as indicated by the clamping plate 46 and clamping bolts 46a through the pedestal. The free end carries a contact 47 cooperating with a contact 48 on the armature 31.

The contacts 47 and 48 provide the make-and-break means for the electro-magnet 45 for operating the armature 31 as a vibrator motor means. The circuit connection for the electro-magnet is completed through one of the mounting springs 32 for the armature, thence through the armature and the contacts 47 and 48, thence through the contact spring 45, bolts 46a, terminals 50, a magnet lead 49, the electro-magnet winding 35, and a second lead 49a, back to the source of supply (not shown). This connection is indicated most effectively in Figs. 2 and 3. 30

It will be noted particularly in Fig. 2, that a resistor element 51 is connected to the lug 50 and one of the terminal lugs 44 for the armature mounting spring 32, thereby placing the resistor in parallel with the operating contacts 47 and 48 for the electro-magnet. Being located in direct connection with the contacts, the resistor may be supported directly by its connection therewith and may be included within the shielded housing for the vibrator unit, thereby preventing the radiation of electrical disturbances from the contacts and contact sparking from which the electrical interference is derived. 35

It will be seen that the armature and pole pieces provide a double air gap 34-34, and that the electro-magnet serves to draw the armature closer to and between the pole pieces, until the armature travels a sufficient distance to withdraw the contact 48 from the flexibly mounted contact 47 and open the electro-magnet circuit. 50 The electro-magnet is then de-energized and the armature is permitted to return under the biasing action of the mounting springs 32 to again close the contacts 47 and 48. 55

It has been found desirable that the fixed contact member 45 be sufficiently flexible to follow the armature a short distance when attracted by the electro-magnet, to permit the contacts 47 and 48 to remain closed over an appreciable portion of the forward movement of the armature, and it has further been found to be desirable that the contact 45 be "stiffness controlled"; that is, have a natural frequency of vibration higher than that of the armature in order that it may follow accurately and without chatter, the movement of the armature as above pointed out. 60

To that end, in the vibrator motor means, as shown and described, the armature mass or body is mounted on supporting spring means providing a relatively long radius of vibration, and the make-and-break contact means is provided with a relatively short spring contact leaf or member 45. 70

It will be noted in Fig. 3, particularly, that the 75

spring contact member 45 is provided with a stop means adjacent to its free or contact end, in the form of an adjustable stop screw 52, threaded at an angle through the pedestal 38 in alignment with said free end of the contact member. A suitable lock nut 53 is provided by which the screw is held in adjustment.

The adjustment is such that the contact member 45 is stopped against the end of the stop screw 52 when the armature 31 has traveled inwardly toward the pole pieces a predetermined distance such that its inertia or momentum will carry it the remaining distance of its travel. The stop screw serves to cause the contacts 47 and 48 to open abruptly at said predetermined point. It has been found that by placing the stop screw at an angle to the plane of the contact member or spring 45, as shown, and for meeting the contact member adjacent to the free end thereof, whipping of said member is prevented.

With this arrangement, having a predetermined mass, the armature may be given a uniform vibratory motion. By proper adjustment of the stop means 52 the excursions of the armature on opposite sides of a central position may be made substantially equal and uniform, as is desirable for circuit controlling devices of this character. It thus provides an effective means for reciprocating a common contact between other spaced contacts for uniform circuit controlling purposes, such as smooth full wave rectification.

In the present example, the armature is, in addition to the contact member 45, caused to meet one or more buffer or spring contact members at either end of its travel or excursion from a central position. The arrangement is such that it is normally held at one end of its travel by the tension or biasing action of the supporting spring leaves 32, being shown in this position in Figs. 1, 3 and 4. It is moved to the opposite end of its travel by inertia and the impulse from the electro-magnet, under control of the contact member 45 and the stop means 52, through opening and closing of the contacts 47 and 48 at the proper points in its travel.

In the present example, two pairs of buffer springs or spring contact members 54 are provided on opposite sides of the armature in opposing relation to each other and on opposite sides of the pedestal 38. The buffer springs or spring contact members are secured at the lower ends by suitable clamping bolts 55 which pass through the pedestal as shown more clearly in Fig. 3. The bolts serve to clamp a pair of opposing springs, and are provided with suitable insulating washers 56 to prevent electrical connection between the pair of springs clamped by the common means.

The spring contact members are substantially parallel with each other and with the spring contact member 45 and the spaced supporting spring leaves 42, standing vertically with respect to the base 27 and being substantially the same length as the supporting springs 32 for the armature mass.

The spring contact members are bent or deformed in the direction of the armature and against the stop fingers, being thereby normally under tension and urged or biased into engagement with stop fingers.

The upper or free ends of the spring contact members are arranged to meet the armature in the region of the limits of its excursions to resiliently stop it. When relieved from contact 76 with the armature the springs are met and

stopped by projecting stop means or fingers 57 provided on the upper end of and integral with the mounting pedestal or post 38. It will be noted that the stop means in connection with the vibrator contact member 45 is provided by the 5 adjustable stop screw or stud 52.

Electrical switching contacts are also provided between the armature and the buffer springs, comprising the contacts 58, 59, 60 and 61, and the contacts 62 cooperating therewith and carried by the armature. The arrangement is such that the armature provides an intermediate common contact movable between pairs of spaced spring contacts or contact elements, for controlling separate circuits hereinafter described. 15

The intermediate common contact provided by the armature, operates to complete each circuit alternately by engaging first with one and then with the other of the two opposing contacts, such as the contacts 58 and 59, or the contacts 60 and 20 61. This is shown more clearly in Fig. 4.

In order that the contacts may be arranged in balanced relation to each other on the armature, the body or mass of the latter is provided by two plates 63 suitably secured together, back to back, 25 by suitable means such as rivets 64, which also secure the supporting springs 32 thereto. The contacts 62 are individually riveted to each plate in order that said contacts may be aligned coaxially in pairs, back to back, as shown in Fig. 4. 30 The contacts are thereby all arranged in opposing balanced relation to each other on opposite sides of the armature and on opposite sides of the make-and-break contact 48.

Sufficient force is imparted to the armature by 35 the supporting springs 32 to raise the buffer or contact springs from the stop fingers slightly as the armature is caused to travel away from the electro-magnet in one direction and to the normal rest position shown in the drawings, whereby 40 the contacts 58 and 60 are firmly closed with the armature contact 62 in the interval during which the buffer springs are out of contact with the stop fingers.

As the armature moves toward the ends of its 45 excursions, that is, towards the spring contact members or buffer springs, such members, being free for movement against the tension of the spring elements, are moved outwardly from the stop fingers when engaged by the armature. Firm 50 closure of the contacts over an extended period is thereby effected, such period ending abruptly with sharp contact break when the spring contact members meet the stop fingers on the return movement. 55

The outer contact members or buffer springs are normally under tension urging said elements into engagement with the stop fingers 57. The latter are rigid and interconnected, being integral with the pedestal or center post 38. The 60 center post or pedestal, with the stop fingers, provides a rigid intermediate member between the buffer springs or spring contact members. The stop means or fingers provide movement limiting means underlying each contact member 65 or element and serve to meet the contact members abruptly on the return movement of the armature therefrom, and thus aid in effecting the sharp break for the contacts above mentioned. 70

The mass of the armature serves to provide sufficient inertia further to aid in effecting positive closing of the contacts over an appreciable interval of time after the buffer springs 54 leave the stop fingers 57 at each end of the armature 75

throw or excursion. Stating the above in other words, after the contacts close, the energy stored in the armature causes it to continue to move against the stiffness of the buffer springs 54 until it is gradually brought to rest, the contacts being in the closed position. The energy thereby stored in the buffer springs with slight loss due to damping is reimparted to the armature on the return movement until the buffer springs strike the stop fingers and the contacts reopen. The closing and opening of the contacts is repeated at the opposite end of the armature movement.

It will, therefore, be seen that the buffer springs, being resilient, and functioning somewhat on the order of bumpers in stopping the movement of the armature, or as combined resilient contact members and buffer or stop means for the armature, also exert a force in reversing the movement of the armature and thus aid in obtaining smooth vibratory action of the armature. The frequency of vibration of the armature in the present example is about 70 cycles per second. A higher frequency may however be provided if desirable or necessary.

It will be noted that the armature is normally located in a retracted position away from the electro-magnet pole pieces and in this position the biasing force of the electro-magnet contact spring 48 is added to that of the buffer springs 54. This added biasing force is balanced in the arrangement shown, by the opposing stiffness in the supporting springs 32 which, as has hereinbefore been stated, are deformed or set to provide a biasing force in the opposite direction and toward the contact spring 45.

With this arrangement the mass of the armature is free to vibrate between the buffer springs and the contacts carried thereby, substantially uniformly on either side of the mid-position, which may be considered as that in which the armature, as the center contact element, is substantially mid-way between the outer contacts.

Referring now to Fig. 5, the vibrator rectifier device of the preceding figures is shown schematically in a circuit diagram for a power supply system, and for the purpose of better understanding the invention, like parts shown in the diagram bear the same reference numerals as in the preceding figures.

The actuating electro-magnet is indicated at 35 in connection with an armature 65 representing the armature and supporting spring construction of the preceding figures. The armature is provided with contacts 62-62 and with a pair of cooperating contacts 58 and 59 and the second pair of cooperating contacts 60 and 61. The electro-magnet operating contacts are indicated at 47 and 48.

The base member of the vibrator rectifier is indicated at 10, and the shield containers are indicated by the enclosure in the dotted outlines 13 and 14. The base 10 is grounded, as indicated at 66. The pair of circuit controlling condensers 19 are located inside the base 10, as is also the shunt resistor 51. The latter is connected with the armature and with the contact 47, as shown, whereby it is connected in shunt to the vibrator or electro-magnet operating contacts 47 and 48.

In the present power supply system and as hereinbefore referred to, a step-up transformer, indicated at 67, is provided in connection with the vibrator contact device to be controlled thereby. The transformer is provided with a divided primary winding 68 and a divided sec-

ondary winding 69, the primary having a center tap 70 and the secondary having a center tap 71.

The transformer is located between a low voltage battery source of current indicated by input supply leads 72 and higher voltage output supply leads 73 for anode and grid circuits and the like, of radio and electronic tube apparatus (not shown).

In the present example, the vibrator device is arranged to connect the input low voltage circuit or leads 72 first across one half and then across the other half of the primary 68 of the transformer 67, while the secondary is similarly alternately connected with the high voltage output circuit or leads 73.

For this purpose the armature 65 is connected, as indicated, by the lead 74 to ground through connection with the casing or base member 10, while the primary terminals are connected through leads indicated at 75, with the primary 20 contact members 60 and 61. The secondary terminals are also similarly connected through leads indicated at 76 with the secondary contact members 58 and 59. The circuit controlling condensers 19 are connected each between one of the 25 secondary contacts 58 and 59 and the ground, through a connection as shown, between the lead 74 and the leads 76.

The low voltage input circuit and the high voltage output circuit are connected together and grounded as indicated at the point 77. With this arrangement the two circuits are interconnected on the low voltage or grounded side, which in the present example is indicated as the negative side of each circuit.

Operating current for the electro-magnet 35 is taken through a supply lead 78 from the positive side of the low voltage input circuit 72, and after passing through the contacts 47 and 48 is returned to the negative side of the said circuit 40 at 77 through the armature, the lead 74 and the base member 10.

With this arrangement the electro-magnet 35, under control of the contacts 47 and 48, causes the armature 65 to vibrate uniformly between the contacts 58 and 60 and the contacts 59 and 61. Through the reversing action of the contacts, a pulsating direct current is applied to the primary in an alternating direction, first through one half and then through the other.

The resulting alternating current set up in the secondary is alternately selected from the secondary contacts 60 and 61 by the armature 65 and returned to ground. As will be seen, the contact arrangement is such that the current flow in the secondary is in a direction from each half toward the positive side of the high voltage output circuit 73, whereby the alternations resulting in the secondary are rectified and applied as a pulsating direct current to the output circuit 73. For the purpose of filtering the output current a condenser 79 is connected preferably adjacent to the terminal 71 of the secondary, across the output circuit.

The ratio of the transformer is such that the 65 low supply voltage at the input circuit 72, which in an automobile radio supply circuit may be of the order of 6-8 volts, is stepped up and applied to the output circuit 73 at a value suitable for use with radio tube circuits such as the anode or 70 output circuits, and for this purpose may be of the order of 270 volts.

Referring now to the modification shown in Figs. 6, 7 and 8, a vibrator unit is shown in which a central core member 85 for an actuating elec-

tro-magnet 86 provides a supporting member for the unit. The electro-magnet winding 86 is located in spaced relation to the ends 87 of the core member, which are formed to be gripped and held in resilient mounting means hereinafter described in connection with the embodiment shown in Fig. 9. The core is preferably cylindrical, as shown, and the ends 87 are of reduced diameter to provide shoulders 88 for preventing longitudinal movement of the core when mounted for use in a vibrator device.

The core is also provided at one end with an extended pole piece 89 having an active pole face 90 with which is associated a vibratory armature 15 or reed 91 having its free end in close spaced relation to the pole face 90, and having a flexible mounting means at the opposite end for holding it rigidly against movement in all directions except that for vibratory movement past the pole 20 face 90.

In the present example, the armature or reed 91 is mounted on a supporting bar 92 extending transversely of the core 88 at the opposite end thereof, substantially parallel with the pole piece 25 89. The armature or reed 91 is flexibly secured to the supporting bar 92 through the medium of a flat strip 93 of spring material. The strip is sufficiently stiff, however, and is bent or tensioned slightly in a direction to hold the armature 30 in a slightly retracted position eccentric with respect to the center of magnetic force existing at the pole face 90. This position is shown clearly in Fig. 6.

By providing the supporting bar 92 and spring 35 member 93, as well as the armature pole piece and magnet core, of magnetic material, it will be seen that the construction above described provides substantially a closed magnetic circuit having a single air gap 94 which is relatively narrow. It will also be noted that the pole piece 89 is 40 provided with an elongated pole face extending along and in the same direction as the armature body to present a relatively large flux diffusing area to the armature.

45 At the opposite ends of the electro-magnet winding and between the pole piece 89 at one end and the supporting bar 92 for the armature at the opposite end, are spaced washers or supporting plates 95 and 96, of insulating material, preferably substantially rectangular in form. The ends of the plates, as indicated at 97 and 98, surround the armature and form spaced supporting and insulating means for the current carrying and other elements of the vibrator.

55 In the present example, the armature is grounded to the core. However, it will be appreciated that in case it is desired to provide an insulated armature the strip of resilient spring material 93 may be formed of resilient insulating material.

60 Furthermore, the armature, while forming part of the magnetic circuit of the electro-magnet 86, also provides a common contact carrying member or element between two spaced buffer springs or outer contact carrying elements 99 and 100 for 65 effecting vibratory switching connection with external circuits such as are shown hereinafter.

The buffer springs or contact elements are preferably of thin, flat, current-conducting spring material and are mounted at one end as indicated at 101 on the insulating support or plate 96, in opposing spaced relation to each other on opposite sides of the armature and substantially in the plane of vibrational movement of the latter.

75 At their free ends, the buffer or contact springs

99 and 100 are bent inwardly toward each other and the armature to provide switching contact with the armature, as shown more clearly in Fig. 6. For this purpose, the armature is provided with contacts 102, and contacts 103 and 104 5 are carried, respectively, by the free ends of the buffer or contact springs 99 and 100 in alignment with the contacts 102 and in close relation thereto so that the armature travel is relatively short to effect a switching operation of the armature from one contact to the other.

In the present example, the armature is arranged to close contact with one of the buffer springs as shown when in a normally de-energized position slightly eccentric to the center of the pole 15 face 90 and the magnetic field of the electro-magnet. In this position the armature contact is closed with the contact 104 and is in slightly spaced relation to the contact 103.

A desired spaced relation of the outer contacts 20 is maintained by stop means carried by, and preferably integral with the upper washer or mounting member 95. The stop means is provided by slotting the mounting member on each side of the armature as indicated at 105, to provide 25 bridge members 106 forming stop means or fingers, on opposite sides of a central opening 107 for the armature.

With this arrangement, the stop fingers serve to meet the spring contact elements and as the 30 armature moves, cause abrupt separation of the contacts and a corresponding sharp break of circuits which may be controlled by the contacts. The contact and stop finger arrangement is shown more clearly in Fig. 8 in which the armature is 35 shown at the extreme end of its travel after having been under the attraction of the electromagnet when energized.

It will be noted that in this position the buffer or contact spring may be lifted away from the 40 stop fingers, while in the de-energized position shown in Fig. 6 the contact or buffer spring 104 may similarly be raised or lifted from its corresponding stop finger means. This permits the contacts to remain closed over an appreciable 45 period until the contact finger again meets its associated stop finger means. In order that the period of vibration of the armature may be reduced and that the frequency of vibration may be adjusted to a predetermined value the armature 50 may for example be loaded by increasing its mass, preferably at the free end, by suitable means such as a detachable weight 108. In the present example, the stiffness of the armature suspension and buffer springs together with the mass of the 55 armature, is such that the armature is caused to vibrate at a desired frequency.

The armature is caused to vibrate under control of the vibrator contacts which may be separate from the contacts 102, 103 and 104 for 60 switching control. In the present example, one of the vibrator contacts is carried by the armature as indicated at 109 and the other of which is flexibly mounted in cooperative relation thereto as indicated at 110. The contact 109 is carried 65 by the armature on a shorter radius than the main contacts and the associated contact 110 is carried by a spring bracket 111, which lies at one end between the armature and the spring contact member 100, and extends substantially parallel 70 therewith and in spaced relation to both the armature and the spring contact member. The bracket is offset, as shown more clearly in Fig. 7, and is secured to the supporting member 96 in spaced relation to the adjacent spring contact member. 75

The spring bracket 111 is provided with stop finger means 112 for causing proper separation of the contacts 109 and 110. The stop finger is carried by a bracket 113 and extends between the armature and the spring bracket 111 adjacent to the vibrator contacts 109 and 110 adjacent to the free end of the spring bracket 111. The bracket is secured as shown preferably on the outer end 98 of the mounting member 96.

5 The contacts 109 and 110 correspond to the contacts 47 and 48 of the embodiment of the invention hereinbefore described, and serve to control the electro-magnet in substantially the same manner, that is, as the armature is attracted by the electro-magnet the contacts 109 and 110 open at a predetermined point determined by the stop finger 112 and cause the electro-magnet to be de-energized. The armature continues under the momentum imparted to it by 10 the impulse from the electro-magnet and continues on until the operating contacts are closed in the opposite direction and its force is expended in meeting the stiffness of the buffer or contact spring, whereupon it is returned under the biasing 15 action of its spring mounting and the energy stored in the buffer or contact spring, and upon 20 closure of the contacts the cycle is repeated.

With the arrangement shown, the armature is free to vibrate without danger of striking the 25 pole piece, since it swings in a plane substantially paralleling the plane of the pole face and closely adjacent thereto. The armature is supported for movement along, but never in contact with the pole face.

30 The flat, flexible spring element 93 provides a resilient mounting device by which the armature is normally held in eccentric position relative to the center of the magnetic field of the pole piece and by which the armature is maintained for 35 reciprocation along said face in close proximity thereto, but out of contact therewith.

Viewed in one of its aspects, the vibrator unit in the present example may be considered to comprise three spaced contact elements which extend in approximate parallelism in the same direction, being formed of resilient material and supported at one end. Intermediate, or stop members are disposed between the central element and each of the outer elements, which outer 40 elements are normally under a tension urging them into engagement with said stop members.

The stop means or intermediate members are integral with the supporting member or bracket and are, therefore, interconnected. In the present construction they are rigid, being connected rigidly by the supporting member with the core of the electro-magnet. Since the core and the stop fingers are thus interconnected rigidly, the 45 relation of the stop fingers and the pole piece is fixed and predetermined.

The above relation is preferably such that with the armature arranged to move uniformly between the spaced outer elements or contacts, it lies normally at rest eccentric to the pole face and the magnetic field, substantially as shown in 50 Fig. 6. The armature thus tends to move into and out of alignment with the pole piece along and adjacent to the pole face and slightly out of contact therewith to provide a relatively narrow air gap.

55 Referring now to Fig. 9 in which like parts throughout bear the same reference numerals as in Figs. 6, 7 and 8, the vibrator unit is shown mounted at its ends in resilient blocks 115 of sound and vibration absorbing material such as

soft rubber, which are adapted to be pressed, as shown, into aligned openings 116 in a base member 117 and the arm 118 of a pedestal 119 integral with or carried by the base 117. The vibrator unit is arranged to be supported in a vertical position between the base and the pedestal arm. Each of the blocks of resilient material is provided with a buffer washer 120 of harder material surrounding the shouldered ends 87 of the core 55

10 The vibrator unit is enclosed by the base 117 and a cooperating open ended shield can 122, which is arranged to surround the base and to seat at its upper end on the pedestal arm to which it is secured by a suitable means such as a screw 15 122. The shield can is lined with sound insulating or absorbing material 124, thereby providing with the base member 117, a closed container for the vibrator unit, having sound and electrical shielding.

20 The electro-magnet 86 is arranged to be intermittently energized through the operation of the contacts 102 and 103 whereby separate operating contacts therefor are eliminated. In addition, this modification is provided with a flat bar 25 pole piece indicated at 125, lying in a position to attract the armature 91 toward it to reduce the air gap indicated at 126. This provides a simplified pole piece construction, but has the disadvantage that the armature approaches the pole 30 piece. The air gap may, however, be adjusted by bending the pole piece 125 or in other suitable manner, so that the armature is stopped by the stiffness of the buffer or contact spring 98, without striking the pole piece.

35 The electro-magnet 86 is provided with terminal leads 127 and 128, which are connected respectively to a terminal 130 for the contact spring 99 and to a terminal 129 for the armature 91, as indicated. The arrangement is such that the 40 electro-magnet for operating the vibrator is connected in parallel with the intermediate common movable contact element, provided by the armature, and an outer contact element toward which the armature is moved in response to energization of the electro-magnet, whereby the 45 electro-magnet is shunted out upon establishment of the circuit controlling contacts.

50 Stated in other words, the vibrator device is arranged to include two spaced normally opened circuit controlling contact devices, one of which serves in the movement of the armature to make and break intermittently, a circuit through the electro-magnet, and thereby to cause vibration of the armature. The contacts are connected, 55 therefore, in a circuit which is closed to de-energize the electro-magnet when the contact device is closed.

The switching arrangement provided by the vibratory contact device is jointly utilized to control the energization of a transformer 131. For this purpose the transformer primary, indicated at 132, is provided with a center tap connection 133 with one side of a power supply circuit 134, while the terminals of the primary winding are 60 connected through leads 135 with the two outer contact elements 99 and 100. The armature is connected to the opposite side of the supply circuit 134 through a supply lead 136.

65 With this arrangement it will be seen that the supply circuit 134, when energized, causes the electro-magnet 86 to be energized and alternately deenergized by opening and closing of the contacts 102 and 103 as a shunt circuit therefor. At the same time, the alternate closing of the 70 75

contacts 102 on the armature with the contacts 103 and 104, causes each half of the primary winding 132 to be energized alternately. This establishes across the terminals 137 of the secondary winding 138 an alternating voltage which is thus derived from any suitable low voltage direct current source (not shown) which may be connected with the supply leads 134.

The voltage established across the terminals 10 at 137 is dependent upon the step-up ratio of the 10 transformer and may be utilized in any suitable manner, or may be rectified in accordance with the arrangement shown in the preceding embodiment of the invention by the provision of additional secondary contacts, or by other suitable means.

It will be seen that the electro-magnet energizing circuit is taken through one half of the primary winding, which is the lower half of the 20 winding as viewed in the drawings. This arrangement has the advantage of simplifying the apparatus, but since the operating contacts for the vibrator motor means or electro-magnet and the circuit controlling contacts are the same, separate individual adjustment of the two sets of contacts is not possible.

Since this embodiment of the invention is otherwise the same as the embodiment shown in Figs. 6, 7 and 8, further description is not believed to be necessary.

The vibrator device may be arranged for plug-in connection with the transformer and other portions of the circuit. For example, the base may be provided with plug-in contacts as terminals for the supply leads, thereby providing for the easy removal and replacement of the device in an electrical apparatus.

A plug-in arrangement is particularly desirable in the case of portable and automotive radio 40 apparatus, where the vibrator unit may require frequent inspection as a result of use under unusual and adverse operating conditions.

It is at present preferred that the base of the unit be provided with plug-in terminals and in 45 Fig. 10, to which attention is now directed, a modification of the base of the device shown in Figs. 1 to 4 inclusive, is shown as adapted for plug-in connection.

Referring to Fig. 10, the base of the vibrator 50 unit is indicated at 140 and is provided with stepped spaced threaded portions 141 and 142 for receiving screw-threaded shielding means such as is shown in the foregoing figures above referred to. The apparatus well is reduced in 55 width and elongated as indicated at 143, to provide space at the bottom of the base for the insertion of suitably insulated plug-in type of terminal pins 144. The terminal pins may be located on either or both sides of the well as shown 60 in the drawings and project from the base a sufficient distance to readily be gripped by any suitable cooperating contact means (not shown).

The contact pins are preferably insulated from each other and the base by being mounted in an 65 insulating plate 145 pressed into a suitable recess 146 in the base. It will be noted that the apparatus well 143 is connected with the base through a web above the insulating plate and that the web is provided with openings through which the 70 lead wire connections to the interior apparatus is made. As plug-in connection means for radio tubes and like devices are well known, further description is believed to be unnecessary.

It will be seen, however, that in each of the 75 embodiments of the invention the vibrator per se

is mounted as a unit within a closed substantially soundproof electrically shielded casing providing for resiliently retaining the vibrator unit in substantially a vertical position. It will also be seen that the armature in each embodiment extends in a vertical direction, thereby particularly adapting the device for use in portable electrical and radio apparatus for the reason that the device may be mounted so that the plane of movement of the armature is transverse of the base and at a right angle to one or both of the directions of movement to which the apparatus is subjected in use. The armature is, therefore, substantially unaffected by motion in the directions above mentioned.

It will further be seen that in each embodiment of the invention, the vibrator device is provided with a relatively heavy base member on which a removable shield and sound proof members are mounted to enclose the vibrator unit. The unit, 20 as disclosed in Figs. 6 to 9, inclusive, has the advantage that it may be mounted by inserting the ends of the core member in resilient mounting blocks in the casing or frame provided therefor.

In the several embodiments of the invention, 25 the mass of the vibrator unit per se is such that its natural frequency of vibration is lower than that of the armature, whereby vibratory movement of the unit does not appreciably affect the vibratory action of the armature. In the embodiment of Figs. 1 to 4, inclusive, the electro-magnet is mounted at one end of the base or pedestal, while the armature supporting spring contact members or reeds are mounted on what may be regarded as the opposite end of the base or the 35 base proper. In each embodiment of the invention, the resilient contact members are mounted to stand vertically and extend substantially parallel with each other with the free ends at the top of the device adjacent to the electro-magnet pole 40 piece or pole pieces.

We claim as our invention:

1. A vibratory circuit controlling device comprising in combination a base member, and a vibrator unit resiliently mounted thereon in spaced relation thereto, said unit including an armature mounted to vibrate in a plane substantially at a right angle to and transverse of the base member, and said unit having a mass and stiffness such that its natural period of vibration is longer than the vibrational period of the armature.

2. A vibratory circuit controlling device comprising in combination a base member, and a vibrator unit resiliently mounted thereon in spaced relation thereto, said unit including an armature mounted to vibrate in a plane substantially at a right angle to and transverse of the base, and said unit having a mass and stiffness such that its natural period of vibration is longer than the period of vibration of the armature, resilient spring contact members arranged in contacting relation with the armature to meet the latter at the ends of its vibrational movement, one of said members having a length and stiffness such that its natural period of vibration is shorter than that of the armature, whereby in connection with the armature such member is stiffness controlled.

3. A vibratory circuit controlling device comprising in combination a base member, and a vibrator unit resiliently mounted thereon in spaced relation thereto, said unit including an armature mounted to vibrate in a plane substantially perpendicular to and transverse of the base, and said

unit having a mass and stiffness such that its natural period of vibration is longer than the vibrational period of the armature, and a pair of nested spaced shield cans removably mounted on said base through the medium of screw-threaded connections therewith and providing with the base shielded enclosure means for the vibrator unit.

4. An electrical vibrator unit comprising a base, 10 an electro-magnet supported from and lying in a plane substantially at a right angle to and intersecting said base, said electro-magnet having a pair of pole pieces providing spaced parallel pole faces extending transversely of the base, a 15 vibratory armature having a body movable between said pole faces but out of contact therewith, flexible spring mounting means for said armature secured to the base and having a free end carrying said armature body, a plurality of elongated 20 spring contact members extending substantially parallel with said spring mounting means from the base and having free ends arranged in contacting relation to the armature on opposite sides thereof, one of said contact springs being relatively short and having a natural frequency of vibration higher than the period of vibration of the armature, and said vibrator unit having a natural frequency of vibration lower than that of the armature, and means for mounting said 25 device whereby said vibrator unit stands in a vertical position whereby the plane of vibration of the armature may be oriented to extend in a predetermined direction.

5. An electrical vibrator unit comprising a base 30 member having an annular groove, a vibrator unit having a base provided with a second annular groove, and a sleeve of resilient material interlocking at its ends with said grooves and providing spacing and connection means between said 35 40 base member and said vibrator base.

6. An electrical vibrator unit comprising a base member having an annular groove, a vibrator unit having a base provided with a second annular groove, and a sleeve of resilient material 45 interlocking at its ends with said grooves and providing a resilient connection between said base member and said vibrator base, said base member having a plurality of stepped spaced threaded peripheral surfaces substantially coaxial with said 50 first named groove for receiving correspondingly threaded shield members for said unit.

7. An electrical vibrator unit comprising a base member having an annular groove, a vibrator unit having a base provided with a second annular 55 groove, and a sleeve of resilient material interlocking at its ends with said grooves and providing a resilient connection between said base member and said vibrator base, and said base member being provided with projecting plug-in terminal 60 members.

8. A vibrator unit comprising in combination a base, a pedestal member extending substantially vertically from the base, elongated spring contact members extending along said pedestal, each being secured to said pedestal at one end adjacent to the base and having free contact bearing ends arranged in opposing relation to each other on opposite sides of the pedestal member, said spring contact members being biased against said pedestal member, a vibratory armature means movable in contacting relation with and between said free ends of said members, said armature means including spring members secured to the pedestal adjacent to said base and extending therefrom 70 substantially parallel with said spring contact

members, and an electro-magnet supported from and located in spaced relation to said base in association with said armature means.

9. A vibratory circuit controlling device comprising in combination a base member, and a vibrator unit resiliently mounted thereon in spaced relation thereto, said unit including an armature mounted to vibrate in a plane substantially at a right angle to and transverse of the base, and said unit having a mass and stiffness such that its 10 natural period of vibration is longer than the vibrational period of the armature, an electro-magnet associated with said armature, operating contact means for controlling said electro-magnet including a spring contact member fixed at one 15 end and having a free end in contacting relation to the armature, said member having a natural period of vibration shorter than that of the armature whereby said member is stiffness controlled, and means including an adjustable stop screw 20 arranged to contact with the free end of said contact member to open said contact means.

10. A vibratory circuit controlling device comprising in combination a base member, and a vibrator unit resiliently mounted thereon in spaced 25 relation thereto, said unit including an armature mounted to vibrate in a plane substantially at a right angle to and transverse of the base, a pair of nested spaced shield cans removably mounted on said base through the medium of screw-threaded connections therewith and providing with the base shielded enclosure means for the 30 vibrator unit, circuit controlling contact means associated with said armature for operation thereby, and a pair of circuit controlling condensers connected with certain of said circuit controlling contact means mounted on said base member within the confines of said enclosure means.

11. A vibratory circuit controlling device comprising in combination a base member, and a vibrator unit resiliently mounted thereon in spaced relation thereto, said unit including an armature mounted to vibrate in a plane substantially at a right angle to and transverse of the base, a pair 45 of nested spaced shield cans removably mounted on said base through the medium of screw-threaded connections therewith and providing with the base shielded enclosure means for the vibrator unit, means providing a well depending 50 from said base member and communicating with the interior of said enclosure means, electric circuit controlling impedance elements mounted in said well, and means for sealing said well about said impedance elements.

12. A vibratory circuit controlling device comprising in combination a base member, and a vibrator unit resiliently mounted thereon in spaced relation thereto, said unit including an armature mounted to vibrate in a plane substantially at a 55 right angle to and transverse of the base, a pair of nested spaced shield cans removably mounted on said base through the medium of screw-threaded connections therewith and providing with the base shielded enclosure means for the vibrator unit, said shield cans being of metallic material providing relatively thin walls, and means providing a sound absorbing lining on the interior of at least one of said shield cans.

13. A vibrator device comprising a base member, a plurality of shield containers releasably mounted thereon in spaced relation to each other and a vibrator unit mounted on said base member for inclusion within said shield containers, said unit comprising a base, a sleeve of resilient 70 75

- material providing a flexible connection between said base and base member, an armature mounted on said base for vibratory movement in a vertical plane transverse to the base and vibratory contact means for controlling the operation of the armature having a period of vibration shorter than that of the armature and resiliently contacting therewith whereby said contact means is stiffness controlled.
10. 14. A vibratory contact circuit controlling device comprising, in combination, a relatively heavy base member having a series of threaded cylindrical surfaces thereon in stepped spaced relation to each other, a plurality of nested shield containers threaded on said surfaces, a vibrator unit associated with said base member, a resilient connecting member having flexible tapered walls between said base member and said unit and holding said unit in spaced relation to said base member, an armature member mounted for vibratory movement in a plane transverse of said base member and at substantially a right angle thereto, an actuating electro-magnet for said armature member having spaced pole pieces for receiving said armature member between them, contacts for controlling the operation of said electro-magnet, and a fixed spring contact member for one of said contacts arranged to contact with the armature, said contact member having a natural frequency of vibration higher than that of the armature whereby it is stiffness controlled in connection with the armature.
15. 15. A vibratory contact circuit controlling device comprising, in combination, a vibrator unit and an electrically shielded substantially sound-proof housing for said unit having a base member and a plurality of nested shield cans mounted thereon in spaced relation to each other, said vibrator unit comprising a base, an electro-magnet mounted in spaced relation to the base and having spaced pole pieces, means providing an armature body movable toward and between said pole pieces in close spaced relation thereto without striking the same, spaced supporting springs for the armature body, said springs extending at a right angle to the base, a spring contact member on each side of the armature extending substantially at a right angle to and from the base and having free ends disposed in spaced relation to the armature body, said spring contact members being bent in the direction of the armature for contact therewith, intermediate stop members for holding said springs in spaced relation to each other and a tapered sleeve of resilient material providing a flexible connection between said base member and said base whereby the latter is resiliently held in spaced relation to said base member.
20. 16. In a vibratory contact circuit controlling device, a vibrator unit comprising an insulating base, a pedestal of insulating material mounted thereon, a bracket on said pedestal, an electro-magnet mounted on said bracket and having spaced pole pieces, an armature mass, spaced supporting springs for said armature mass comprising elongated strips of resilient material having curled edges adjacent to the armature mass and being secured to said pedestal and base, the armature mass being supported on the free ends thereof for movement between but out of contact with the pole pieces, a spring contact member mounted on said pedestal and having a free end disposed adjacent to and in contacting relation with the armature mass, said spring contact member being shorter than said supporting
25. springs, a pair of elongated spring contact members on opposite sides of the pedestal secured to said pedestal and base and extending substantially parallel with said spaced supporting springs with free ends on opposite sides and in opposing relation to the armature mass, means providing cooperating circuit controlling contacts between the armature and said spring contact members, and projecting stop means for said contact members carried by the upper end of said pedestal.
30. 17. An electrical vibrator unit comprising a base, an electro-magnet supported from and lying in a plane substantially at a right angle to and intersecting said base, said electro-magnet having a pair of pole pieces providing spaced parallel pole faces extending transversely of the base, a vibratory armature having a body movable between said pole faces but out of contact therewith, flexible spring mounting means for said armature secured to the base and having free ends carrying said armature body, a plurality of elongated spring contact members extending substantially parallel with said spring mounting means from the base and having free ends arranged in contacting relation to the armature on opposite sides thereof, one of said contact springs being relatively short and having a natural frequency of vibration higher than that of the armature, and said vibrator unit having a natural frequency of vibration lower than the period of vibration of the armature, and adjustable stop means for said last named one of said contact springs adapted to meet said contact spring adjacent to the free end thereof.
35. 18. A vibratory circuit controlling device comprising in combination a base member, and a vibrator unit resiliently mounted thereon in spaced relation thereto, said unit including an armature mounted to vibrate in a plane substantially at a right angle to and transverse of the base, a pair of nested spaced shield cans removably mounted on said base through the medium of screw-threaded connections therewith and providing with the base shielded enclosure means for the vibrator unit, electro-magnet motor means for actuating said armature including a spring contact element mounted in contacting relation at one end with the armature, a resistor having common terminal connection with said spring contact member whereby it is included within the enclosure means, a plurality of spaced circuit controlling contact elements associated with the armature for controlling separate circuits, and a pair of circuit controlling impedance elements mounted in said base member within the confines of said enclosure means and electrically connected with the armature and two of said spaced circuit controlling contact members, whereby said circuit controlling impedance elements are included within the confines of said shielded enclosure means.
40. 19. A circuit making and breaking device comprising, in combination, an elongated casing, an electro-magnet mounted in one end of said casing and having pole faces located substantially in a plane transverse of said casing, three spaced contacts mounted in the other end of said casing and extending toward said electro-magnet, said contacts being formed of resilient material with the center of one of said contacts extending to a point substantially adjacent to said pole faces, an armature carried by the end of the center contact for swinging movement past said pole faces, said armature being normally dis-

posed eccentrically with respect to said pole faces so that energization of the electro-magnet will produce movement of said armature and swing said center contact into circuit closing engagement with one of the outer contacts, the other of said outer contacts being engageable by said center contact upon a return movement thereof when the electro-magnet is de-energized, said outer contacts being resiliently urged toward each other, and spacing fingers interposed between said outer contacts for abutment thereby to limit the inward movement thereof.

20. A circuit making and breaking device for a direct current transforming system comprising spaced contacts controlling separate circuits in said system, an intermediate and common contact for completing either circuit, means for reciprocating said common contact between said spaced contacts, all of said contacts being of resilient material and the spaced contacts being under a tension which urges said spaced contacts toward said common contact, and stop means underlying each of said spaced contacts for engagement therewith near the free ends thereof.

25. 21. A circuit making and breaking device for a direct current transforming system comprising spaced contacts controlling separate circuits in said system, an intermediate and common contact for completing either circuit, means for reciprocating said common contact between said spaced contacts, all of said contacts being of resilient material and the spaced contacts being under a tension which urges said spaced contacts toward said common contact, a limit finger underlying each of said spaced contacts for engagement therewith, and means connecting said fingers and maintaining a spaced relationship therebetween.

22. A circuit making and breaking device having the combination of three spaced contact elements formed of resilient material and supported at one end, intermediate members disposed between said elements, the outer elements being normally under a tension urging said elements into engagement with said members near the free ends thereof to define their proper adjustment relative to the center element, and means for reciprocating said center element into circuit closing contact alternately with said outer elements.

50. 23. In a circuit making and breaking device, the combination of three spaced contact elements formed of resilient material and supported at one end to extend in approximate parallelism in the same direction, intermediate members disposed between said elements, the outer elements being normally under a tension urging said elements

into engagement with said members near the free ends thereof, and an electro-magnet energizable to move said center element into contact with one of said outer elements and de-energizable to release said element for return movement into engagement with the opposite element.

5. 24. In a circuit making and breaking device, the combination of three spaced contact elements formed of resilient material and supported by one end, intermediate members disposed between said elements, the outer elements being normally under a tension urging said elements into engagement with said members near the free ends thereof to define their proper adjustment relative to the center element, and means for reciprocating 15 said center element into circuit closing contact alternately with said outer elements, said outer elements being free for movement against the tension thereof when engaged by said center element.

20. 25. In a circuit making and breaking device, the combination of contact elements for alternately closing a plurality of circuits including spaced contacts and a movable resilient element, an electro-magnet, and an armature on said movable element disposed within the effective range of said electro-magnet, said armature in the normal position of said movable element being located eccentrically of said range for movement to establish one circuit immediately upon energization of said electro-magnet, said armature having a mass ample to carry said movable element in an opposite direction for completing another circuit upon de-energization of said electro-magnet.

25. 30. 35. 40. 45. 50. 55. 26. In a circuit controlling means the combination of a base, an electro-magnet mounted at one end of said base and having an active pole face located in a transverse plane relative to the base, a reed mounted on the other end of the base and having a free end terminating adjacent to said pole face, an armature mounted on said free end and supported by the reed for swinging movement in a plane substantially paralleling the plane of said face and closely adjacent thereto, a pair of fixed contacts located one on either side of said reed, contact means on said reed engageable with either of said fixed contacts in the movement of said reed, said reed having a normally idle position at one side of the center of magnetic attraction of said active face, and means for intermittently energizing said electro-magnet.
